SWITCH CONSTRUCTION

Nicholas G. Polgov, Chicago, Ill., assignor to
 Delta-Star Electric Company, Chicago, Ill., a
 corporation of Illinois

Application September 2, 1942, Serial No. 457,017

5 Claims. (Cl. 200—169)

My invention relates, generally, to electric switch constructions and it has particular relation to the construction of what are known as air type disconnecting switches.

An object of my invention is to provide for locking a switch blade of a disconnecting switch in the open position as well as in the closed position.

Another object of my invention is to provide a single means for operating both locking means and also moving the switch blade to and from the closed position.

Other objects of my invention will, in part, be obvious and in part appear hereinafter.

For a more complete understanding of the nature and scope of my invention reference may be had to the following detailed description taken in connection with the accompanying drawings in which:

Figure 1 is a view, in side elevation, of a preferred embodiment of my improved form of disconnecting switch construction;

Figure 2 is a view, in front elevation, of the construction shown in Figure 1;

Figure 3 is a view, in side elevation, of a portion of the switch blade shown in Figure 1 and showing the same at an enlarged scale and the details of the locking mechanisms and common operating means therefor;

Figure 4 is a view, similar to that shown in Figure 3, but showing the switch blade in the open rather than the closed position; and

Figure 5 is a view, in side elevation, of another embodiment of the invention.

Referring now to the drawings, and particularly to Figures 1 and 2, it will be observed that the reference character 10 designates, generally, an air type disconnecting switch in which the present invention is embodied. The disconnecting switch 10 is arranged to control the connection between a stud 11 which may be connected into a suitable bus structure or the like, and a stud 12 which may extend from a conventional form of circuit breaker, such as an oil filled or air blast circuit breaker. The stud 11 is carried by an insulator bushing 13 which is suitably mounted on a support structure 14. The stud 12, as is conventional practice, extends through an insulating bushing 15 and is carried thereby. The stud 12 and the bushing 15 extend through a wall or cover 16 of the circuit breaker and are suitably mounted as will be readily understood.

Threaded on the lower end of the stud 11 is a stationary switch member 20 which, as shown more clearly in Figures 3 and 4 of the drawings, is provided with a V-shaped opening 21 for re-

ceiving a bolt 22 which extends through and holds in place a pair of switch blade members 23 and 24. It will be understood that the two switch blade members 23 and 24 together constitute a single switch blade and that they are movable as a unit to and from the switch closed position. The opposite sides of the stationary switch member are provided with contact surfaces 25 for receiving deformed or raised portions 26 from the switch blade members 23 and 24 to provide substantially line contact engagement therebetween as is conventional practice.

It will be observed that the switch blade members 23 and 24 are pivoted by means of a bolt 30 on a hinge arm 31 that is secured by suitable clamp means to the upper end of the stud 12. The opposite sides of the upper end of the hinge arm 31 are provided with contact surfaces as indicated at 32 in Figures 3 and 4 of the drawings 15 for contact engagement with a circular deformed or ridge portion 33 in each of the switch blade members 23 and 24. This construction provides substantially line contact as will be readily understood.

With a view to locking the switch blade members 23 and 24 in the switch closed position, as shown in Figure 3 of the drawings, the stationary switch member 20 is provided with a notch or recess 34 into which a bolt 35 fits. The bolt 35 is guided between pins 36 extending through the switch blade members 23 and 24. The bolt 35 is also guided on a pin 37 which extends through the switch blade members 23 and 24 and through a slot in the bolt 35. A coil compression spring 38 is provided in the slot in the bolt 35, as indicated, between the pin 37 and one end of the slot so as to bias the bolt 35 into the recess 34. The bolt 35 is provided with a head portion 39 with which shoulders 40 on an operating arm 41 are arranged 20 to cooperate for lifting the bolt 35 out of locking engagement with the recess 34.

The operating arm 41 is pivotally mounted between the switch blade members 23 and 24 by means of pins 42 which extend transversely therethrough. The movement of the operating arm 41 is limited by the slotted openings 43 therein. An operating eye 44 is provided in the operating arm 41 for receiving the prong of a switch stick which is employed for opening and closing disconnecting switches and the like when they are energized or likely to be energized.

As indicated hereinbefore it is desirable to lock the switch blade members 23 and 24 in the open position as shown in Figure 4 of the drawings. 25 For this purpose a second bolt 48 is provided

which is similar to the bolt 35 previously described. The bolt 48 is arranged to interfit with a recess 49 which is located in the upper end of the hinge arm 31 as illustrated in the drawings. The bolt 48 is slidably mounted between the switch blade members 23 and 24 between a pair of transversely extending pins 50. The bolt 48 is also guided by a transversely extending pin 51 which extends through a centrally located slot in which a coil compression spring 52 is also located. The coil compression spring 52 tends to bias the bolt 48 into locking engagement with the recess 49.

With a view to moving the bolt 48 to the unlocked position a linkage comprising three links 53, 54 and 55 is provided between the switch blade members 23 and 24. It will be observed that the link 53 is pivoted by means of a pin 56 to the operating arm 41. The links 53 and 54 are pivoted together by a pin 57. A pin 58 transversely extending through the switch blade members 23 and 24 pivotally mounts the link 54 therebetween. The links 54 and 55 are pivoted together by means of a pin 59. In reality the links 53, 54 and 55 each comprise a pair of spaced link members which for convenience are herein termed links.

A pin 60 extends through the lower end of the link 55 and through slots 61 in the switch blade members 23 and 24 whereby it is guided for operation. The pin 60 extends under one side of a head 62 of the bolt 48 for the purpose of withdrawing the same to unlock the switch blade members 23 and 24 so as to permit their movement from the open position to the closed position.

In describing the operation of the switch construction herein disclosed it will first be assumed that the switch is in the closed position as illustrated in Figures 1, 2 and 3 of the drawings. In this position the bolt 35 is locked in the recess 34 and must be withdrawn therefrom to permit opening of the switch blade members 23 and 24. In this position the bolt 48 is in the unlocked position and rides upon the circular upper end portion of the hinge arm 31 as illustrated more clearly in Figure 3 of the drawings.

Now the prong of a switch stick is inserted in the eye 44 of the operating arm 41 and by exerting a pull through the switch stick in a direction substantially normal to the length of the switch blade this operating arm is rotated slightly in a counterclockwise direction as permitted by the left hand slot 43. This movement of the operating arm 41 is sufficient to pull the bolt 35 down out of the recess 34 and the continued application of a pull to the operating arm 41 then causes the switch blade members 23 and 24 to rotate about the bolt 30 on the hinge member 31. The movement of the switch blade members 23 and 24 continues until they occupy the full open position as shown in Figure 4 of the drawings. It should be noted that this counterclockwise direction of rotation of the operating arm 41 corresponds to the counterclockwise direction of rotation of the switch blade as it swings into open position around the hinge pin 30. Thus, one continuous pulling movement transmitted through the switch stick to the apertured end 44 of the operating arm in a direction substantially at right angles to the length of the switch blade first rotates the arm 41 in a counterclockwise direction and then rotates the switch blade in a counterclockwise direction to the open position shown in Figure 4.

In the full open position the bolt 48 is biased by the spring 52 into locking engagement with the recess 49 and thereby holds the switch blade members 23 and 24 in the full open position. Now when it is desired to close the switch 10, the prong of a switch stick is inserted in the eye 44 and a pushing or thrusting force is transmitted through the switch stick to the eye 44 in a direction substantially at right angles to the length of the switch blade, which causes the operating arm 41 to rotate in a clockwise direction. This rotation of the operating arm 41 relative to the switch blade members 23 and 24 is limited by the upper slot 43 as viewed in Figure 4 of the drawings. During this clockwise rotation of the operating arm 41 the motion thereof is communicated by the links 53, 54 and 55 to the bolt 48 and it is withdrawn from the recess 49. The continued application of force to the operating arm 41 then holds the bolt 48 in the unlocked position and causes the switch blade members 23 and 24 to swing in a clockwise direction around the hinge pin 30 to the switch closed position as shown in Figure 3 of the drawings. Thus, one continuous pushing motion transmitted through the switch stick first revolves the arm 41 in a clockwise direction, and then revolves the switch blade in a clockwise direction.

In Figure 5 of the drawings there is shown another embodiment of my invention illustrating a construction that can be employed when the spacing between the stationary switch members is relatively close. As there shown, an upper stationary switch member 70 is provided and mounted on a suitable insulator 71. A lower stationary switch member 72 is provided in alignment with the upper switch member 70, and it is carried by a suitable insulator 73. The switch members 70 and 72 are arranged to be interconnected by a switch blade 74. The switch blade 74 preferably comprises two switch blade members, similar to the construction previously described. Obviously, if additional current carrying capacity is required, the switch blade 74 can be duplicated, as desired, to provide the required current carrying capacity between the switch members 70 and 72.

The switch blade 74 is pivotally mounted on the upper switch member 70 by a bolt 75. A bolt 76 extends through the lower end of the switch blade 74 and is arranged to interfit with a V-shaped opening 77 in the lower switch member 72. It will be observed that the construction of the switch blade 74 and its mounting in cooperation with the switch members 70 and 72 is similar to that described hereinbefore in connection with the switch construction shown in Figures 1 through 4 of the drawings.

It will be observed that the stationary switch member 70 is provided with two recesses 80 and 81, corresponding to the closed and open positions of the switch blade 74, and that they are adapted to receive a bolt 82 which is slidably carried by the switch blade 74. The bolt 82 is similar to the bolts 35 and 48, previously described, and includes a coil compression spring 83 which serves to bias it into the recess 80 or 81, depending upon the position of the switch blade 74. The bolt 82 is guided on a pin 84 extending through the switch blade 74. Arms 85 extend from the inner end of the bolt 82 to permit operation thereof, as will be presently described.

Another bolt 86, similar in construction to the bolt 82, just described, is also slidably mounted

on the switch blade 74 and is arranged to cooperate with a locking recess 87 in the lower stationary switch member 72 for locking the switch blade 74 in the switch closed position.

For the purpose of withdrawing the bolts 82 and 86 from their respective recesses and for the further purpose of moving the switch blade 74 from and to the switch closed position, an arm 88 is pivotally mounted intermediate the ends of the switch blade 74 by a bolt 89 extending through the switch blade. The arm 88 is provided with an integrally formed eye portion 90 for receiving the prong of a switch stick, as will be readily understood, to permit operation of the switch by an operator. The arm 88 is also provided with integrally formed bosses 91 which are arranged to cooperate with the arms 85 of the bolts 82 and 86 for withdrawing them when the arm 88 is rotated.

In describing the operation of the switch shown in Figure 5 of the drawings, it will be assumed that the switch blade 74 is in the switch closed position as indicated by the full lines. In order to move the switch blade 74 to the alternate position shown by the broken lines, the prong of a switch stick is inserted in the eye 90 and by exerting an outward pull on the switch stick in a direction substantially at right angles to the length of the switch blade the arm 88 is rotated in the clockwise direction indicated by the arrow 93. At the same time, two of the bosses 91 are rotated in the directions indicated by the arrows 94 and 95 to engage the adjacent arms 85 of the bolts 82 and 86. Continued clockwise rotation of the arm 88 causes the withdrawal of the bolts 82 and 86 from their respective locking recesses 80 and 87 in the switch members 70 and 72, respectively. The switch blade 74 can now be rotated in a clockwise direction to the alternate open position by the continued application of force to the arm 88. When the switch blade 74 reaches the position shown by the broken lines, the arm 88 is released and the bolt 82 is operated by its spring 83 into locking engagement with the recess 81 in the upper stationary switch member 70.

It will be observed that a V-shaped boss or ridge 92 is integrally formed with the arm 88 on the side of the switch blade 74 away from the eye portion 90. The purpose of this ridge or boss 92 is to permit the arm 88 to rotate slightly without moving the switch blade 74 so as to insure that the bolts 82 and 86 are withdrawn from their respective locking recesses before any force is applied to the switch blade 74 for rotating it to the alternate position. No movement of the switch blade 74 takes place until the arm 88 has been rotated sufficiently far to bring one side or the other of the boss or ridge 92 into engagement with the adjacent edge of the switch blade 74.

When the switch blade 74 is to be moved from the open position, as shown by the broken lines, to the closed position, the foregoing sequence of operations is reversed. That is, the arm 88 is rotated in a counterclockwise direction around the pivot pin 89 to first withdraw the bolt 82 from the locking recess 81. At the same time, the bolt 86 is withdrawn to a position so that it can clear the upper portion of the lower stationary switch member 72 when the switch blade 74 is rotated back in a counterclockwise direction to the closed position as shown by the full lines.

Since it is obvious that certain changes can be made in the foregoing switch construction with-

out departing from the scope and spirit of the present invention, it is intended that all matter shown in the accompanying drawings or described hereinbefore shall be interpreted as illustrative and not in a limiting sense.

I claim as my invention:

1. A switch construction comprising, in combination, a pair of stationary switch members in insulated spaced relation, a switch blade pivoted to one of said switch members and adapted to be moved into and out of engagement with the other switch member, each of said switch members having a locking recess therein, a first spring-pressed bolt slidably carried by said switch blade for interfitting with the locking recess in said other switch member to lock the switch blade in the closed position, a second spring-pressed bolt slidably carried by said switch blade for interfitting with the locking recess in said one switch member to lock said switch blade in the open position, an operating arm projecting outwardly and upwardly from the edge of said switch blade, means for mounting said arm on the switch blade comprising a pair of laterally spaced slots in said operating arm and a pair of pins carried by said blade engaging in said slots, said operating arm having swiveling movement relatively to said switch blade by virtue of sliding movement of said slots relatively to said pins, and means establishing operating connections between said operating lever and said first and second spring-pressed bolts whereby an outward pull exerted on said operating arm will release and swing said blade to open position, and whereby an inward push exerted on said operating arm will release and swing said blade to closed position.

2. A switch construction comprising, in combination, a pair of stationary switch members in insulated spaced relation and each having a locking recess therein, a switch blade pivoted to one of said switch members and adapted to be moved into and out of engagement with the other switch member, a first spring-pressed bolt slidably carried by said switch blade for interfitting with the locking recess in said other switch member to lock the switch blade in the closed position, a second spring-pressed bolt slidably carried by said switch blade for interfitting with the locking recess in said one switch member to lock the switch blade in the open position, each of said spring-pressed bolts being of T formation having laterally extending side arms, an operating lever pivotally mounted on said switch blade at a pivot point between said spring-pressed bolts, a first pair of pins projecting from said operating lever for engaging with the two side arms of said first spring-pressed bolt, and a second pair of pins projecting from said operating lever for engaging with the two side arms of said second spring-pressed bolt, whereby an outward pull exerted on said operating lever in a direction substantially at right angles to the length of the blade will release and swing said blade to open position, and whereby a push exerted on said operating lever in a direction substantially at right angles to the length of the blade will release and swing said blade to closed position.

3. In an electric switch, the combination of a hinge terminal, a contact terminal, a hinge pin carried by said hinge terminal, a switch blade having pivotal mounting on said hinge pin for swinging motion into and out of contact with said contact terminal, switch-open locking means

for locking said blade to said hinge terminal in the switch-open position of said blade, switch-closed locking means for locking said blade to said contact terminal in the switch-closed position of said blade, an operating arm moving with said switch blade and provided with an apertured end to receive a switch stick, said arm having pivot means for pivotally mounting it on said switch blade, said operating arm extending laterally and outwardly from said switch blade to dispose the apertured end of said arm laterally from the adjacent edge of the switch blade and closer to the free end of said blade than the pivot means on which said arm is mounted, whereby an outward pull exerted by the switch stick on the apertured end of said arm in a direction substantially at right angles to the length of said switch blade causes said operating arm to pivot relative to its pivot means in the same direction of rotation as said blade revolves on said hinge pin in swinging from closed position to open position, and whereby a pushing force exerted by the switch stick on the apertured end of said arm in a direction substantially at right angles to the length of said switch blade causes said operating arm to pivot relative to its pivot means in the same direction of rotation as said blade revolves on said hinge pin in swinging from open position to closed position, and means for transmitting motion from said operating arm to said switch-open locking means and to said switch-closed locking means.

4. In an electric switch, the combination of a hinge terminal, a contact terminal, a hinge pin carried by said hinge terminal, a switch blade having pivotal mounting on said hinge pin for swinging motion into and out of contact with said contact terminal, spring pressed switch-open locking means for locking said blade to said hinge terminal in the switch open position of said blade, spring pressed switch-closed locking means for locking said blade to said contact terminal in the switch-closed position of said blade, an operating arm moving with said switch blade and provided with an apertured end to receive a switch stick, said arm having pivot means for pivotally mounting it on said switch blade, said operating arm extending laterally and outwardly from said switch blade to dispose the apertured end of said

arm laterally from the adjacent edge of the blade and closer to the free end of said blade than the pivot means on which said arm is mounted, whereby an outward pull exerted by the switch stick on the apertured end of said arm in a direction substantially at right angles to the length of said blade causes said operating arm to pivot relative to its pivot means in the same direction of rotation as said blade revolves on said hinge pin in swinging from closed position to open position, and means for transmitting releasing motion from said operating arm to said switch-open locking means and to said switch-closed locking means.

5. In an electric switch, the combination of a hinge terminal, a contact terminal, a hinge pin carried by said hinge terminal, a switch blade having pivotal mounting on said hinge pin for swinging motion into and out of contact with said contact terminal, switch-open locking means carried by said blade for locking said blade to said hinge terminal in the switch-open position of said blade, switch-closed locking means carried by said blade for locking said blade to said contact terminal in the switch-closed position of said blade, an operating arm pivotally mounted on said blade on pivot means which permits said arm to pivot selectively in either a clockwise direction or a counterclockwise direction from a normal position relatively to said blade, said operating arm having an actuating end adapted to be engaged by a switch stick or the like for actuating the switch, and means for transmitting motion from said operating arm to said switch-open locking means and to said switch-closed locking means, said operating arm extending laterally and outwardly from said switch blade whereby when the switch blade is to be moved in a counterclockwise direction from one position to another a preparatory counterclockwise rotation is first transmitted to said operating arm for releasing one of said locking means, and whereby when the switch blade is to be moved in a clockwise direction from one position to another a preparatory clockwise rotation is first transmitted to said operating arm for releasing the other of said locking means.

NICHOLAS G. POLGOV.
